CLAIM

We claim the ornamental design for a foldably constructed tray, as shown and described.

DESCRIPTION

FIG. 1 is a top front isometric view of a foldably constructed tray in an unfolded configuration.

FIG. 2 is a top plan view of tray of FIG. 1 in the unfolded configuration.

FIG. 3 is a bottom plan view of the tray of FIG. 1 in the unfolded configuration.

FIG. 4 is a front elevation view of the tray of FIG. 1 in the unfolded configuration.

FIG. 5 is a rear elevation view of the tray of FIG. 1 in the unfolded configuration.

FIG. 6 is a left side elevation view of the tray of FIG. 1 in the unfolded configuration.

FIG. 7 is a right side elevation view of the tray of FIG. 1 in the unfolded configuration; and,

FIG. 8 is a top front isometric view the tray of FIG. 1 in the folded configuration.

The dotted lines represent fold lines and are part of the claim. The broken lines represent environment and form no part of the claim.

1 Claim, 5 Drawing Sheets
